INDICATING APPARATUS FOR CASH REGISTERS

Russell W. Lynch, Chicago, Ill.

Application December 11, 1930
Serial No. 501,685

2 Claims. (Cl. 235—23)

This invention relates to electric indicating apparatus and is particularly adapted for use with cash registers.

A primary object of the invention is to provide an electric indicating apparatus of simple and compact construction which is adapted to indicate through the illumination of light bulbs the amount of the purchase recorded by a cash register. Another object is to provide simple mechanism by which transactions recorded by a cash register may be indicated by the illumination of a sign which may be separate from the cash register and which may be visible from several directions. Another object is to arrange such electrical illuminating apparatus in compact form so that it may be used as an attachment for cash registers now in use. Other objects and advantages will appear as the specification proceeds.

The invention is fully described in the following specification and shown in the accompanying drawings, in which—

Figure 1 is a side view of a cash register equipped with one form of electric indicating device embodying my invention; Fig. 2 is a rear view 26 in elevation; Fig. 3 is a broken sectional view, the section being taken as indicated at line 3 of Fig. 2; Fig. 4 is an enlarged sectional view of one of the distributor tubes shown in Fig. 3; Fig. 5 is a plan view of the distributor tube; Fig. 6 is a rear view of the cash register and attachment device with a portion of the wall broken away; Fig. 7 is an enlarged plan view of an electric light bulb panel or frame; Fig. 8 is a sectional view of the panel, the section being taken as indicated at line 8 of Fig. 7; Fig. 9 is an enlarged sectional view of one of the light bulb sockets; Fig. 10 is a plan view of the electric indicating apparatus, the top having been removed; and Fig. 11 is a schematic view of the wiring lay-out.

40 In the illustration given A represents a cash register provided with a casing extension B. The register may be provided with the usual parts for recording a purchase and with plates or bands upon which numbers have been painted or formed. The extension casing B of cash registers now in use are usually provided with openings C through which the amounts recorded by the cash register are visible to the customer and dealer. The cash registers are also usually provided with a plurality of spaced gears D which are carried by a shaft supported within the extension B. The gears D are usually five in number.

45 In the embodiment of my invention illustrated in the drawings, the electric indicating appa-

ratus is housed within a casing 1 which is provided with a reduced depending portion 2 adapted to extend into the casing extension B of the cash register. The casing portion 2 may be connected to extension B by screws or other suitable means.

In the illustration given, the casing member 1 is substantially square and is provided on each side with a rectangular opening 3 behind which is secured a pane of glass 4. Secured to the side walls of casing 1 are the angle-irons 5 which provide horizontal flanges 6. The flanges 6 support the light frame member 7 and also the distributor tube support 8.

The bulb frame 7, in the illustration given, 70 comprises a pair of spaced walls 9 having partitions 10 dividing the frame into a plurality of compartments. As shown more clearly in Fig. 10, each side of the frame 7 has five compartments.

75 Each frame compartment is adapted to receive a bulb-socket panel 11. Details of the panel are shown more clearly in Figs. 7, 8 and 9. Preferably the panel is formed of a fiber board 12 covered with a copper strip 13. As shown more clearly in Fig. 9, the copper sheet 13 is drawn into an opening 14 in the fiber board to form a cup-shaped socket for an electric light bulb. The socket portion of the copper sheet is subjected to pressure to form threads adapted to receive the 80 attachment end of a light bulb. The inner ends 15 of the copper sheet are turned inwardly to support a fiber disk 16 through which extends a contact stud 17.

Connected to the studs 17 of the bulb sockets 90 are connecting wires 18 which are connected at their other ends to contact studs 19 carried by the distributor tubes 20. As shown more clearly in Figs. 4 and 5, each of the distributor tubes 20 preferably comprises a cylindrical body member 21 which is formed of any suitable insulating material and top and bottom members 22 and 23 which close the ends of the cylindrical member 21. The bottom member 23 is centrally apertured to receive a plunger member 24 which carries a plurality of spaced metal disks 25. A spring 26 normally urges the plunger in a downward direction. When the plunger is in lowered position, the disks 25 are out of engagement with the studs 19 but when the plunger is raised, the disks 100 are brought into engagement with the contact studs 19. The distributor tubes 20 are secured to and supported by the supporting bar 8. If desired, a cable or sheath 27 may be used to enclose the wires 18 leading from a distributor tube 110

to a particular light bulb panel. The wires 18 are insulated.

As shown more clearly in Figure 10, the distributor tubes 20 are arranged in five rows, each 5 row being supported by a cross-piece 8. There are ten distributor tubes in each of the rows. Each row carries wires leading to a particular bulb socket panel in each side of the frame 7; and the wires from each tube in that row lead to certain light bulb sockets. As illustrated in 10 Fig. 10, the fifth tube from the bottom in the first row has wires leading to one panel in each side of the frame 7 and the wires are connected to certain light bulbs which upon illumination, will 15 form the numeral "5".

To actuate each row of the plungers 24, a movable contact member 28 having a rounded or cam surface is employed. As illustrated more clearly in Fig. 3, each of the contact members 28 is provided with an insulating block or base 29 which is secured to a rack member 30. The rack 30 is provided near its ends with pins 31 which extend into slots 32 formed in guide members 33 supported on opposite sides of the rack 30. As shown 20 more clearly in Fig. 6, the guide members are secured at their ends to the casing 1 and a pair of guide members support each of the rack members 30.

Any suitable means for connecting one of the 30 racks 30 to one of the gears D of the cash register may be used. In the illustration, a shaft 34 is mounted in the reduced casing portion 2 and carries a plurality of spaced pinions 35 adapted to mesh with gears D. The pinion gears 35 also 35 mesh with the racks 30.

Referring more particularly to Fig. 3, a wire 36 is connected to each movable contact member 28 and is preferably looped loosely within the casing member 2 so as to permit longitudinal movement of the contact member. Another wire 40 37 is connected to the copper plates of the bulb socket panels, thus completing the circuit.

It is preferred to keep the circuit broken until the members 28 have been brought in contact with the proper plungers 24, in order to prevent flashing of lights as the members 28 travel under the rows of plungers. Any suitable means for accomplishing this purpose may be used. For example a circuit breaker 38, of any suitable type 45 may be installed in the line 36 and may be operated by the drawer of the cash register, the plunger 39, which normally breaks the circuit, being forced outwardly by spring means and permitting the contact members to come together, when the drawer of the register is withdrawn. Since in the normal operation of a cash register, the drawer is opened after the other operations 50 of the cash register have come to a stop, the circuit in my apparatus will be closed after the mechanical operations have been completed and after the proper lights have been brought 55 within the circuit by the contact members 28. If it is desired to operate the illuminating apparatus independently of the drawer, any other suitable means for closing and breaking the circuit 60 may be used, such means, of course, being adapted to break the circuit after a brief illumination of the light globes and to close the circuit immediately after the actuated contact members come to rest.

As shown more clearly in Fig. 6, the various gears D of the cash register, usually five in number, are connected by the apparatus heretofore described to rows of distributor tubes from which 70 wires lead to the proper bulb panels. In this way

the dollar and cents indicators of the cash register are made to correspond with similarly arranged panels on the four sides of my apparatus. In the illustration given (Figs. 3 and 10), the contact member 28 is shown in contact with the 80 plunger number 5 in the left hand row of distributor tubes, thus forming in the \$100.00 column the numeral 5.

In the operation of the apparatus, the gears D of the cash register rotate the pinion gears 35 85 which are rotatably mounted upon fixed shaft 34 and cause the rack members 30 to move in a horizontal plane. When the gears D come to rest, the contact members 28 raise certain of the plungers so as to form contacts between the 90 contact members 28 and the wires leading from the distributor tubes. When the drawer is opened so as to permit the circuit breaker 38 to close the circuit, the current may pass through the wires 36, the contact members 28, plungers 95 24, disks 25, contact studs 19 and wires 18 to the particular light bulbs to which the wires are secured. From the bulbs, the current passes through the copper plate 13 and the wire 37. The particular bulbs in the circuit are illuminated and a numeral is formed in each of the panels 100 which corresponds to the transaction recorded by the cash register. When the drawer is closed, the circuit is broken again by the breaker 38, and the illumination ceases.

The apparatus has been illustrated in the form of an attachment which may be used with cash registers already in use. The reduced casing portion 2 may be readily secured to casing extension B of the cash register. If desired, however, the electric light panels may be supported in another part of the room and at some distance from the cash register, or they may be used in another room.

While I have shown an apparatus adapted to 115 be actuated by the gears of a cash register, it is obvious that suitable connecting and contact means may be used with cash registers which are not provided with gears of the type illustrated but are equipped with other means for 120 displaying a record of the purchase, without departing from the spirit of my invention. It is obvious also, that the illuminated panel apparatus of the character described may be operated by connections with parts of the cash register 125 other than those illustrated and that the illuminating apparatus may be built in the cash register, as an integral part thereof, rather than as an attachment.

The foregoing detailed description has been 130 given for clearness of understanding only and no unnecessary limitations should be understood therefrom, but the appended claims should be construed as broadly as permissible in view of the prior art.

I claim:

1. In combination with a differentially movable indicator element of a cash register or the like, a frame, a plurality of lights supported therein and adapted to outline different digits 140 by different combinations of the lights, a plurality of stationary distributor contact members supported in the frame and arranged in relatively spaced relation, each member having contacts adapted to cause illumination of the lights for 145 a certain digit, and a movable contact member connected for movement with an indicator element and adapted when differentially positioned to cause the contacts of a selected distributor member to be closed.

2. In combination with a differentially movable indicator element of a cash register or the like, a four-sided frame, a plurality of lights supported upon each side of the frame and adapted to outline different digits by different combinations of the lights, a plurality of stationary distributor contact members carried by the frame and arranged in relatively spaced relation, each member having contacts and connections therewith adapted to cause illumination of the lights for a certain digit on each side of the frame, and a movable contact member connected for movement with an indicating element and adapted when differentially positioned to cause the contacts of a selected distributor member to be closed. 80
